INVENTOR

WILLIAM H. STOKES

BY *John C. Atkinson* *Attnorneys*

UNITED STATES PATENT OFFICE.

WILLIAM HENRY STOKES, OF COVENTRY, ENGLAND, ASSIGNOR TO COURTAULDS, LIMITED, OF LONDON, ENGLAND.

BOBBIN.

1,368,069.

Specification of Letters Patent.

Patented Feb. 8, 1921.

Application filed June 2, 1920. Serial No. 386,141.

To all whom it may concern:

Be it known that I, WILLIAM HENRY STOKES, a subject of the King of Great Britain, residing at 2 Lydgate road, Coventry, 5 in the county of Warwick, England, have invented new and useful Bobbins, of which the following is a specification.

The object of this invention is to provide means by which the washing, or otherwise 10 treating, with liquid, of artificial filaments, fibers, or the like, wound upon bodies, such as bobbins, can be effected in a more expeditious, economical and efficient, manner than hitherto.

Such filaments, fibers, or the like, are, 15 after being formed in the coagulating bath, usually wound on to bobbins made of impervious acid-resisting material (such, for instance, as glass, or stoneware,) and are 20 afterward washed to free them from chemicals and by-products and then the said filaments, fibers, or the like, then being dried and subsequently removed from the bobbins for further treatment. Owing to the thickness 25 of the layers of closely wound material upon the bobbins the washing process has been slow and the result not satisfactory.

The object of the present invention is to overcome these difficulties and effect economy 30 in the number of bobbins and quantity of washing water, or other liquid, required in carrying on the process and at the same time effect the washing in a more expeditious, complete and satisfactory way than 35 hitherto.

According to this invention the bobbins, 40 or equivalent devices, which carry the filaments, fibers, or the like, are provided with porous, reticulated, or equivalent, material which will afford drainage for the filaments, fibers, or the like, wound thereon and allow of the ready passage through, or between, them of the washing water, or the like. Such porous, reticulated, or equivalent, material may, for example, be metal 45 gauze, or other material which will resist corrosion, such as knitted, or woven, fibrous material (cotton, or wool, for example), readily pervious to liquid. The said material may be applied in any suitable way; for example, it may be in tubular form, passed onto the bobbins, or it may be in strip form which can be held on the bobbins by sewing, or the material can be secured 50 by means of any suitable devices, such, for instance, as rings, or bands.

The accompanying drawing shows in elevation in Figure 1, in longitudinal section in Fig. 2 and in Fig. 3 in plan partly in transverse section (on the line $\alpha\alpha$ Fig. 2) 60 an example of a bobbin provided with material suitable for the purposes of this invention, but it is to be understood the invention is not limited to the use of this precise example.

a represents the bobbin, b represents the porous, reticulated, or equivalent, material such as fabric of cotton, wool or other material of a character and formation which will not cause injury to the silk, and with 70 which the said bobbin is provided in accordance with this invention and c represents the filaments, fibers, or the like, wound upon the said material b .

It will be evident that the invention is not 75 limited to the use of any particular material as any material which will answer the purpose, as regards supporting the filaments, fibers, or the like, and allowing of the passage of liquid and will not be objectionably acted upon by the chemicals with which it comes in contact, may be employed and it will also be evident that any suitable bodies other than bobbins may also be used 80 and that, although we have specially referred to washing, the invention can also be applied in connection with operations, other than washing, in which liquids are required to be passed through materials wound, or supported, upon bobbins, or other bodies. 85

What I claim is:—

1. A bobbin having an imperforate exterior, and a liquid-permeable sleeve thereon upon which the fiber to be treated is wound, and through which a treating fluid 95 will readily pass between the wound fiber and the exterior of the bobbin.

2. A bobbin having an imperforate exterior, and a textile spacing sleeve thereon upon which the fiber to be treated is wound, and through which a treating fluid will readily pass between the wound fiber and the exterior of the bobbin.

In testimony whereof I have signed my name to this specification in the presence of 105 two subscribing witnesses.

WILLIAM HENRY STOKES.
